UNITED STATES PATENT OFFICE.

BERRY ANDERSON BROWN, OF FRANKLIN, OHIO.

DESIGN FOR A HEAD-PROTECTOR.

SPECIFICATION forming part of Design No. 33,843, dated January 1, 1901.

Application filed December 1, 1900. Serial No. 38,373. Term of patent 7 years.

To all whom it may concern:

Be it known that I, BERRY ANDERSON BROWN, a citizen of the United States, residing at Franklin, in the county of Warren and 5 State of Ohio, have invented and produced a new and original Design for Head-Protectors; and I do declare the following to be a full, clear, and exact description of the same, reference being had to the accompanying drawings, forming a part thereof.

This invention relates to a new and original design for a head-protector; and it has for its object to provide a design of this character which shall be both useful and ornamental.

The leading feature of the design resides in a pair of similar oppositely-arranged separate muff-pieces, each being of an approximately ogee form and provided with rounded terminal end arms and at one side edge between such arms with offset rounded lobes.

Another distinctive feature of the design resides in a tape or strap extending across the interval between and connecting the terminal arms of the opposite muff-pieces at one end thereof and a similar tape or strap connecting the offset-lobe portions of the opposite muff-pieces.

A minor feature of the design resides in the 30 tapes or strings joined to the disconnected terminal end arms of the muff-pieces.

In the drawings, Figure 1 is a perspective view of a head-protector embodying the herein-described design. Fig. 2 is a plan view 35 thereof.

Referring particularly to the illustration of the design in the drawings, the numerals 1 1 designate the pair of muff-pieces. These muff-pieces 1 are of similar or duplicate formation and are arranged in oppositely-separated relation, with an interval therebetween throughout their entire extent. Each of these muff-pieces is of a general or approximate ogee form and is provided with rounded terminal end arms 2 and at one side edge between or intermediate of said arms with an offset rounded or convexed lobe 3.

A tape or strap (designated by the numeral 4) extends across the interval between and connects the terminal arms 2 of the opposite 50 muff-pieces at one end of the latter, and a similar tape or strap 5 is arranged between and connects the side lobe portions 3 of the said opposite muff-pieces.

In the drawings the opposite muff-pieces 55 are illustrated as being also provided at their disconnected terminals or end arms with tapes or strings 6.

Having thus described the invention, what is claimed as new, and desired to be secured 60 by Letters Patent, is—

The design for a head - protector herein shown and described.

BERRY ANDERSON BROWN.
